UNITED STATES PATENT OFFICE.

CYRUS HOWARD HAPGOOD, OF NUTLEY, NEW JERSEY, ASSIGNOR TO THE DE LAVAL SEPARATOR COMPANY, OF NEW YORK, N. Y., A CORPORATION OF NEW JERSEY.

PROCESS FOR RECLAIMING OIL FROM METAL CHIPS.

Application filed September 6, 1923. Serial No. 661,148.

To all whom it may concern:

Be it known that I, CYRUS HOWARD HAPGOOD, a citizen of the United States, residing at Nutley, county of Essex, and State of New Jersey, have invented a new and useful Improvement in Processes for Reclaiming Oil from Metal Chips, of which the following is a full, clear, and exact description, reference being had to the accompanying drawings, which form a part of this specification.

In machining operations involving the use of cutting oil, a great deal of oil adheres to the metal shavings and chips. In large plants the volume of oil thus carried away may amount to hundreds of gallons per day. It is found to be economical to devote considerable labor and expense to the reclaiming of this oil. One of the most successful and economical of these reclaiming operations comprises a crusher for breaking up the long shavings and reducing them to chips small enough to be readily handled. A mass of these chips is then introduced into a centrifugal basket or extractor, into which steam is introduced. The steam or water of condensation drives the oil off the metal surfaces and water and oil are discharged from the basket by centrifugal force. The oil is subsequently recovered from the water by settlement or otherwise. This process involves the employment of considerable manual labor in the introduction and removal of the chips from the centrifuge, in opening and closing the basket, etc. By no means all the oil is recovered. For example, numerous pockets are formed by the chips in the centrifuge, into which pockets oil is thrown by centrifugal force. These pockets retain more or less oil at the conclusion of the centrifugal operation. Notwithstanding the expense, and the incomplete recovery of oil, the proportion of oil reclaimed is considerable and its value exceeds the expense of recovery.

The object of my invention is to provide a new process whereby the expense of installation of reclaiming machinery and the amount of manual labor required will be much reduced, the chips will be treated continuously instead of being handled in batches, and the proportion of oil reclaimed will be materially increased.

The drawing is a side view, somewhat diagrammatic, of an apparatus in which my process is preferably carried out.

Within a tank *b* is mounted a rotary, open-ended drum or cylinder *c*, supported so that its axis is inclined to the horizontal. From a crusher *a*, or other form of disintegrator, extends a chute *d* communicating with the higher end of the drum. The drum may be rotated by any convenient means, such as a sprocket chain *e* extending from a sprocket wheel *f* on a driving shaft *g*. From the bottom of the tank, beneath and beyond the lower end of the drum, extends upwardly, through and above the top of the tank, a conveyor *h* of any approved type. The tank *b* should be closed, except to allow the extension thereinto of the chute *d*, the driving chain *f* and the conveyor *h*, and except for an opening *i* for hot water and an overflow opening *j* for water and oil, as herein-after described.

Beneath and beyond the upper end of the conveyor *h* is a pivoted platform *k*, held normally in a horizontal position by means of a weight *m*, but adapted to drop into the inclined position shown in broken lines when a given weight of material is deposited thereon. The platform is perforated to allow drainage into a chamber *n*, which may communicate with the interior of the tank *b*. A car *o*, or any other convenient receiver, is positioned to receive the material discharged from the platform when the latter is tilted.

The operation of the apparatus described is as follows: The metallic shavings, etc., are reduced to chips in the crusher or disintegrator *a* and pass down the chute *d* into the cylinder *c*, which continuously rotates at a low rate of speed. The entire cylinder is immersed in a body of water, which should be heated to a fairly high temperature, say about 180° F. The water level, as shown in the drawing, is maintained constant by the overflow outlet *j*.

By the rotation of the cylinder *c* the chips in the cylinder are more or less agitated to expose their surfaces to the action of the hot water, which has a greater affinity than the metal surfaces for the oil. The released or washed off oil, by reason of its lower specific gravity, floats to the upper part of the drum

and escapes from the higher end thereof, thence rising to the surface of the water body, and, together with some water, floating out the overflow *j*. It will be observed 5 that the outlet *j* is located directly opposite a point just above the higher end of the drum, so that the oil emerging from that end of the drum will be free to rise in a direct vertical line onto the surface of the water opposite the outlet.

10 The metal chips, almost completely free from oil, are carried up by the conveyor *h* and deposited on the platform *k*, where the water, with any oil carried in suspension 15 thereby, drain into the chamber *n*. After a sufficient weight of oil-free chips accumulates on the platform *k*, it tilts and deposits its contents into the car *o*, the weight *m* immediately afterward returning the platform 20 *k* to its normal position.

25 The oil and water mixture outflowing through the orifice *j*, flows through a pipe *p* into a centrifugal separator or purifier *s*. This separator is of the closed bowl type, of 30 which a good example is found in Fig. 1 of a patent issued to me July 3, 1923, No. 1,460,718. In this centrifuge the oil and water are separated by centrifugal force, the oil being discharged into a receiver *r*, 35 while the water, containing a little oil, is discharged into a receiver *t*, and is thence pumped through a pipe *u* into the hot water supply pipe communicating with the tank inlet *z*.

35 The advantages of my new process are as follows:

40 The process is continuous and practically automatic and involves no manual labor other than that incidental to general oversight.

45 An almost complete reclamation of the oil is secured. The moderate agitation to which the chips are subjected brings every area of the metal into repeated contact with the hot water, which is as effective as steam in removing the oil. Any very small percentage 50 of oil that is carried, with the water, on the chips discharged by the conveyor, drains off and is conserved. Any oil that is discharged by the centrifugal bowl from the water outlet is returned to the tank. During no part 55 of the process, therefore, can any measurable quantity of oil escape.

55 The apparatus required is inexpensive. The tank, cylinder, chute, conveyor and tilting weighted platform, are simple mechanical elements and can be cheaply constructed and assembled. The cost of these is much less than the cost of a basket centrifuge, 60 traveling crane and other apparatus required in the most effective prior process.

65 It is obvious that the process can be carried out in apparatus other than the one described, which, however, is especially well 70 adapted for the purpose.

If the cutting oil to be reclaimed is mostly mineral oil, it may be advisable to add soda ash, or a prepared soap such as "Gold Dust", or some other oil removing agent, to the water in the tank, and it is to be understood that in specifying water in the claims, I mean to include, as equivalents, all oil washes that may be advisable or necessary to substitute for hot water, in order to operate the process effectively.

75 Having now fully described my invention, what I claim and desire to protect by Letters Patent is:

1. The steps in the process of reclaiming oil from metal chips, which comprises feeding the chips into a body of hot water, progressively feeding the chips forward as they are fed to the body of water and during their forward feed subjecting them to agitation, whereby the hot water removes the oil from the chips as they advance, continuously floating off the oil rising to the surface of the body of water, and continuously withdrawing from the body of water the chips at the forward end of the progressively moving stream of chips.

2. The process of reclaiming oil from metal chips, which comprises feeding the chips into a body of hot water, progressively feeding the chips forward as they are fed to the body of water and during their forward feed subjecting them to agitation, whereby the hot water removes the oil from the chips as they advance, continuously withdrawing from the body of water the chips at the forward end of the continuously moving stream of chips, allowing the oil to overflow from the body of water, subjecting the oil to the action of centrifugal force to separate therefrom any water that overflows with the oil, and returning the separated water to the tank.

3. The process of reclaiming oil from metal chips which comprises feeding the chips into a body of hot water, progressively feeding the chips forward as they are fed to the body of water and during their forward feed subjecting them to agitation, thereby removing the oil from the chips, floating off oil rising to the surface of the body of water, withdrawing and draining the chips, returning the liquid drained from the chips to the body of water, subjecting the oil that has floated off to the action of centrifugal force to separate therefrom any water that overflows with the oil, and returning the separated water to the tank; thereby insuring against the loss of any of the oil.

4. The steps in the process of reclaiming oil from metal chips, which comprises feeding the chips into a body of hot water, progressively feeding the chips forward as they are fed to the body of water and during their forward feed subjecting them to agita-

tion, whereby the hot water removes the oil from the chips as they advance, continuously withdrawing from the body of water the chips at the forward end of the continuously moving stream of chips, and guiding the oil freed from and rising through the water above the chips in a direction opposite to the direction of travel of the stream of chips and toward the surface of the body of water, and continuously floating off the oil from the 10 surface to which it is guided as specified.

In testimony of which invention, I have hereunto set my hand, at New York, on this 28th day of August, 1923.

CYRUS HOWARD HAPGOOD.
